United States Patent Office.

HUGH H. CRAIGIE, OF NEW YORK, N. Y.

Letters Patent No. 61,811, dated February 5, 1867.

IMPROVEMENT IN WATER-CLOSETS.

The Schedule referred to in these Letters Patent and making part of the same.

TO ALL WHOM IT MAY CONCERN:

Be it known that I, HUGH H. CRAIGIE, of the city and State of New York, have invented, made, and applied to use, a certain new and useful Improvement in Water-Closets; and I do hereby declare the following to be a full, clear, and exact description of the said invention, reference being had to the annexed drawing, making part of this specification, wherein—

Figure 1 is a vertical section of the improved apparatus in position for use.

Figure 2 is an elevation of the cock in the position when the water is running.

Figure 3 is a similar view when the parts are in position, with the cock shut off; and

Figure 4 is a plan, illustrating the action of the cock in regulating the supply of water.

Similar marks of reference denote the same parts.

The present invention is an improvement upon that for which Letters Patent were granted to me March 13, 1866, and consists in an improved horned cam and operating segment, moved by the cock that operates to turn down the jet pipe previous to the water being allowed to pass into the said jet pipe, the cock being freely turned to regulate the force of the jet of water, and upon the reverse movement the water is shut off, and then the jet pipe turned up to its normal position by the action of said disk and horned cam. This improvement prevents the risk of injury that might result in the former mode of construction, in consequence of the teeth of the segments not coming correctly together when they have been separated by the turning of the handle.

In the drawings *a* is a standard attached to the floor, near the side of the water-closet; *b* is an adjustable holder for the cock *f*; said holder being provided with jaws, in vertical flanges, one of which secures the cock by the set-nuts *1*; the other receives a movable thimble, *2*, through which passes the horizontal portion *3*, connecting with the curved jet pipe *f*, at the end of which is a nozzle or rose, or other orifice, for the discharge of the water, when the pipe is turned down, within the water-closet. At the end of the horizontal pipe *3*, a tapering plug is formed, that is ground into the horizontal water-way of the cock *f*, and the thimble *2* acts to keep this tight; but should there be any leak at this point, or from the cock, it passes into the cup *4* of the adjustable holder *b*, whence a pipe, at *5*, conveys the water to the closet or sewer pipe. Between the thimble *2* and the tapering plug, the pipe *3* is provided with a horned cam, *i*, that is of a triangular configuration, and *l* is a segment, upon the plug of the cock, having a hole or hook, at *5*, that, passing below the end of the triangular segment, or horned cam *i*, will turn it, rotating the pipes *3* and *f* so that the latter will occupy a horizontal position; and *6* is a stop to arrest the further movement of the segment *l* as the pipe *f* is turned up. *g* is the supply pipe for the water, and *h* is a handle, coming above the seat, so that the pipe and cock may be operated thereby. When the said handle *h* is turned, the segment *l*, acting on the cam *i*, turns down the pipe *k*, and said disk, being over the flat side of the cam, holds it and the pipe *k* in position; but the handle *h* can be turned back or forth to let in the water through the cock *f*, or regulate the force of the jet, to whatever extent may be desired. When the handle *h* is turned in the opposite direction, the hooked portion *5* of the disk passes below the end of the horned cam *i*, turning it up into the position shown in fig. 3, and shutting off the supply of water.

What I claim, and desire to secure by Letters Patent, is—

1. The adjustable standard and drip-cup, in combination with the cock *f*, and jet pipe *k*, substantially as and for the purposes set forth.
2. I claim the thimble *2*, in combination with the cock *f*, jet pipe *k*, and plug on the pipe *3*, for allowing said pipe *k* to be turned, but keeping the joint water-tight, as set forth.
3. I claim the horned cam *i*, and segment *l*, in combination with the cock *f*, and pipe *k*, for the purposes and as set forth.

I witness whereof I have hereunto set my signature this fourth day of August, 1866.

H. H. CRAIGIE.
